UNITED STATES PATENT OFFICE.

FREDERICK KELLER, OF PATERSON, NEW JERSEY, ASSIGNOR OF ONE-
THIRD TO CHARLES E. ROBERTS AND ONE-THIRD TO BERNHARD
PETZOLD, OF PATERSON, NEW JERSEY.

WIRELESS BURGLAR-ALARM.

No. 857,351.

Specification of Letters Patent.

Patented June 18, 1907.

Application filed October 10, 1906. Serial No. 338,289.

To all whom it may concern:

Be it known that I, FREDERICK KELLER, a citizen of the United States, residing at Paterson, in the county of Passaic and State of New Jersey, have invented a new and useful 5 Wireless Burglar-Alarm, of which the following is a specification.

This invention relates to burglar alarms and has for its object to provide a comparatively simple, inexpensive device of this 10 character designed to be positioned at the lower edge of a door or other closure so that should an attempt be made by an unauthorized person to open the door the actuating 15 means will be released and thereby sound an alarm and at the same time lock the door or window against further movement.

A further object of the invention is to provide a casing or housing having a supporting 20 base pivoted thereto and provided with a vertical stop-pin adapted to engage and prevent vibration of the bell-hammer when the alarm is set and having an off-set portion to permit lateral movement of said hammer 25 when a downward pressure is exerted on said casing.

A further object is to provide the casing with a depending spring arm having a laterally extending locking lip adapted to engage 30 spaced notches or recesses formed in the supporting plate for locking the alarm in operative and inoperative position.

A still further object of the invention is to generally improve this class of devices so as 35 to increase their utility, durability and efficiency as well as to reduce the cost of manufacture.

With these and other objects in view the invention consists in the construction and 40 novel combination and arrangement of parts hereinafter fully described, and illustrated in the accompanying drawings, it being understood that various changes in form, proportions and minor details of construction 45 may be resorted to within the scope of the appended claims.

In the accompanying drawings forming a part of this specification: Figure 1 is a longitudinal sectional view of a burglar alarm 50 constructed in accordance with my invention and showing the same in position at the lower edge of a door. Fig. 2 is an end view of the same, a portion of the casing being

broken away to expose the locking pin. Fig. 3 is a perspective view of the pivoted supporting plate detached. Fig. 4 is a side elevation showing the device in position on a window. Fig. 5 is a perspective view illustrating a modified form of window-engaging 60 spur.

Similar numerals of reference indicate corresponding parts in all of the figures of the drawings.

The improved device consists of a casing or housing preferably wedge-shaped in contour, as shown and comprising a pair of pivotally united sections 5 and 6, the section 6 being provided with oppositely disposed lugs 7 having perforations formed therein for the reception of a pivot pin or rod 8 which extends transversely across the casing at the apex thereof, as shown.

The section 5 is provided with a chamber or compartment 9 in which is arranged a spring-motor of any approved construction 65 including a vibrating hammer 10 adapted to engage a bell or other audible alarm 11.

The hammer 10 is secured to a pin or arbor 12 and extending laterally from said arbor is an angularly disposed arm 13 adapted to engage a stop-pin 14 carried by the section 6.

The stop-pin 14 is provided with an off-set portion 15 adapted to engage the free end of the arm 13 when the upper section 5 is elevated above the section 6 so as to prevent vibration of the hammer 10.

The lower section 6 constitutes a supporting base and is provided at its free end with a vertically disposed lug 16 having a pair of spaced notches or recesses 17 and 18 formed 90 therein for engagement with the laterally extending lip 19 of a spring arm 20, the latter being riveted or otherwise secured to the interior walls of the upper section of the casing, as shown.

It will thus be seen that when the section 5 is elevated the lip 19 will engage the notch 18 and thus support the section 5 in set or operative position and when a downward pull is exerted on said section the lip will ride over 100 the face of the lug 16 and enter the notch 17 thereby locking the section 5 in lowered position.

The enlarged end of the section 5 is inclined or beveled, as indicated at 21 and provided with spaced lugs 22 between which is

pivots mounted a pair of arms 23 terminating in a spear-point 24 adapted to be driven or otherwise embedded in the window-frame when the casing is positioned on one of the sashes of a window. The arms 23 are pivots mounted on a rod 25 connecting the lugs 22 while the pivoted ends of said arms are provided with terminal lugs or hooks 26 adapted to engage the upper face of the casing 5 when the arms are moved to elevated or operative position, as best shown in Fig. 4 of the drawing. The lower section or supporting plate 6 is provided with a finger-opening 27 by means of which the operator may conveniently grasp the section 6 and separate the adjacent ends of said sections when it is desired to shut off the alarm.

The upper section 5 is also provided with one or more openings 28 and the apex or thickened portion of said section is provided with an inclined lug or spur 29 adapted to be driven in the floor or other support and prevent lateral movement of the casing when an attempt is made to open said door.

In operation the motor is wound by introducing a key through the finger opening 27 and positioning the same on the winding-head 30 after which the upper section 5 is elevated until the locking lip 19 engages the notch 18 thus locking the alarm in set or operative position. The casing is then placed in position at the lower edge of a door or other closure with the spur 29 bearing against the floor or in case of a window against the adjacent sash. It will thus be seen that should an attempt be made to open the door the latter will engage the inclined face of section 5 and depress the same thereby causing the locking lip 19 to ride over the face of the lug 16 into engagement with the notch 17. As the section 5 is depressed the arm 13 will clear the off-set portion of the locking pin 14 thereby allowing the hammer to vibrate and causing the alarm to sound continuously until the upper section 5 is again elevated. The pressure of the door on the section 5 will drive the spur 29 into the floor, thus preventing accidental displacement of the casing and locking the door against further movement.

When the device is used in connection with a window, transom, or the like the casing is positioned on the upper rail of one of the sashes and the arms 23 swung upwardly until the hooks 26 engage the upper end of the section 5 after which the piercing point of the impaling member is placed against the window-casing so that should an attempt be made to elevate the sash the upper section 5 will be depressed thus sounding the alarm and at the same time locking the window.

In Fig. 5 of the drawing there is illustrated a modified form of window-engaging hook in which the arms are connected by a transverse bar 31 and provided with a pair of spaced terminals or spurs 32.

From the foregoing description it will be seen that there is provided an extremely simple, inexpensive and efficient device admirably adapted for the attainment of the ends in view.

Having thus described the invention what is claimed is:

1. In a burglar alarm, a casing formed of a plurality of pivotally united sections one of which constitutes a supporting base, means for sounding the alarm when one of the sections is depressed, means for locking the movable section in operative and inoperative position, and an impaling member pivotally mounted for swinging movement on one of the sections of said casing.

2. In a burglar alarm, a casing formed of pivotally united sections one of which constitutes a supporting base, alarm mechanism arranged within the casing and including a vibrating hammer, a stop-pin carried by the base for locking the hammer against vibration when one of said sections is elevated and adapted to permit free movement of the hammer when said section is depressed, means for locking the movable section in elevated and depressed position, and an impaling member pivotally mounted on one of the sections of the casing, and hooks carried by the impaling member and adapted to engage the adjacent casing section when said impaling member is moved to operative position.

3. In a burglar alarm, a casing formed of pivotally united sections one of which constitutes a supporting base, alarm mechanism arranged within the casing and actuated to sound the alarm when one of said sections is depressed, lugs extending laterally from the casing, and an impaling member pivotally mounted between the lugs.

4. In a burglar alarm, a casing formed of pivotally united sections one of which constitutes a supporting base, alarm mechanism arranged within the casing and actuated to sound an alarm when one of said sections is depressed, and an impaling member pivotally mounted on the casing and provided with a hook adapted to engage the casing when said member is moved to operative position.

5. In a burglar alarm, a casing formed of pivotally united sections one of which constitutes a supporting base, alarm mechanism arranged within the casing and actuated to sound an alarm when one of the sections is depressed, said casing having one end thereof of inclined and provided with spaced lugs, and an impaling member pivotally mounted for swinging movement between the lugs and provided with a hook adapted to engage the casing when the member is swung upwardly to operative position.

6. In a burglar alarm, a casing formed of pivotally united sections one of which constitutes a supporting base, alarm mechan-

ism arranged within the casing and actuated to sound an alarm when one of said sections is depressed, a lug extending vertically from a supporting base and provided with spaced notches, a spring depending from the upper 5 inwardly extending lip adapted to engage section of the casing and provided with an the notches in the lug for locking the movable section in operative and inoperative position and an impaling member pivotally mounted for swinging movement on one section of said casing.

7. In a burglar alarm, a casing formed of pivotally united sections one of which constitutes a supporting base, alarm mechanism arranged within the casing and including a 15 vibrating hammer having a laterally extending arm, a stop-pin extending vertically from the supporting plate and provided with an 20 off-set portion adapted to engage the arm of the hammer when the upper section of the casing is elevated, and an impaling member pivotally mounted for swinging movement on one of said sections, said hammer being 25 free to vibrate and sound an alarm when the movable section is depressed.

8. In a burglar alarm, a casing formed of a plurality of pivotally united sections one of which constitutes a supporting base, alarm 30 mechanism carried by one of the sections and actuated to sound an alarm when said section is depressed, a lug extending vertically from the free end of the supporting base and provided with a plurality of spaced 35 notches, there being a finger opening formed in the supporting base at said lug, and a spring arm depending from the upper section and provided with a laterally extending lip adapted to engage the notches in the lug for 40 locking the sections in operative and inoperative position.

9. In a burglar alarm, a substantially triangular shaped casing formed of a plurality

of pivotally united sections one of which constitutes a supporting base and is provided 45 at its free end with a vertically disposed lug having spaced notches formed therein, the opposite section having its reduced end provided with a rearwardly extending spur and its opposite end inclined and provided with 50 spaced lugs, alarm mechanism arranged within the casing and actuated to sound the alarm when one of said sections is depressed, an impaling member pivotally mounted between the lugs and provided with means for 55 engagement with a casing when the member is swung vertically to operative position, and a spring arm depending from one of the sections and provided with a laterally extending lip adapted to engage the notches in the 60 lug, there being a finger-opening formed in the supporting base at said lug.

10. In a burglar alarm, a substantially triangular shaped casing formed of a plurality of pivotally united sections one of which is 65 provided with a chamber and the other with a pair of spaced vertically disposed lugs, a pin extending transversely across the casing and forming a pivotal connection between 70 said sections, alarm mechanism arranged within the chamber and actuated to sound an alarm when one of said sections is depressed, a lug extending vertically from the free end of the lower section and provided with spaced notches, there being a finger- 75 opening formed in said section in advance of the lug, and a spring arm depending from the upper section and provided with a laterally extending lip adapted to engage said notches.

In testimony that I claim the foregoing as 80 my own, I have hereto affixed my signature in the presence of two witnesses.

FREDERICK KELLER.
